UNITED STATES PATENT OFFICE.

WILLARD C. LIPE, OF SYRACUSE, NEW YORK.

NAIL.

SPECIFICATION forming part of Letters Patent No. 510,035, dated December 5, 1893.

Application filed March 11, 1893. Serial No. 465,498. (No model.)

To all whom it may concern:

Be it known that I, WILLARD C. LIPE, of Syracuse, in the county of Onondaga, in the State of New York, have invented new and useful Improvements in Nails, of which the following, taken in connection with the accompanying drawings, is a full, clear, and exact description.

My invention relates to improvements in nails, and has for its object the production of an economically manufactured nail, which firmly engages the article into which it is inserted, and resists to a maximum degree any force applied for withdrawing the same from said article; and to this end it consists, essentially, in a body and spiral ribs or projections upon the body provided with a series of transverse grooves, and in the detail construction and arrangement of the parts, all as herein-after more particularly described and pointed out in the claims.

In describing this invention, reference is had to the accompanying drawings, forming a part of this specification, in which like letters indicate corresponding parts in all the views.

Figure 1 is an elevation of a nail constructed in accordance with my invention. Fig. 2 is a sectional view of a pair of opposing cutters or grooving tools for forming the engaging ribs or projections upon the body of the nail, and Figs. 3 and 4 are elevations of the detached cutters or grooving tools shown at Fig. 2.

It is well known that nails, and particularly those constructed of wire are more or less liable to be readily withdrawn from the article into which they are inserted, and that, for the purpose of obviating this result, wire nails have sometimes been provided with a series of teeth of similar construction formed by opposing dies or other similar contrivances. My invention is differentiated from such nails in that its body is provided with spirally extending ribs or projections which give the nail a slight twisting motion when entering, and which are transversely grooved for enabling the fiber of the article in which the nail is inserted to engage said ribs and prevent a ready withdrawal of the nail.

The body—A—of my improved nail is, at Fig. 1, shown as circular in cross section, and

as provided with a rounding head —a— and a tapering point —a'—, but it will be evident that the body or its head may be otherwise formed, and that the exact contour of said parts forms no material feature of my invention.

—B—B— are spirally extending ribs or projections formed upon the body—A—and preferably only upon its lower extremity, although it is evident that the entire body may be provided with said ribs. These ribs —B—B— are preferably formed by swaging outwardly portions of the outer surface of the body, as will be presently described, and are preferably each formed with transverse grooves —b—b—. The grooves —b—b— preferably extend spirally across the ribs —B—B— but they may extend in a straight line across said ribs if desired. As the nail is inserted the ribs —B—B— give the same a slight twisting movement, and, after the nail is in position, the fiber of the article into which the nail is inserted enters the grooves —b—b—, and the nail resists to a maximum degree the force applied for effecting its withdrawal. The nail is free to twist when entering the article into which it is being driven, since the spiral ribs —B—B— extend to the base of its point, and act as threads, and, as the ribs —B—B— do not extend to the head of the nail, the friction against said article of the nail body, and particularly that portion thereof unprovided with the ribs greatly accelerates the action of the transverse grooves —b—b—, and the nail is thereby effectually prevented from turning. Indeed in practically inserting a nail into a fibrous article it turns slightly in entering with comparative freedom, and, when withdrawn, the transverse grooves of its spiral ribs are filled with broken pieces of the fiber of said article.

To further facilitate the entrance of the nail the grooves —b—b— are preferably formed of less depth than the height of the ribs —B—B—, but it will be evident that, without materially departing from my invention, said grooves —b—b— may be as deep as the height of the ribs —B—B—.

It is evident that the ribs —B—B— may be formed by any suitable cutting or swaging apparatus, and I have here illustrated a very simple construction which economically, prac-

tically, and effectively swages said ribs upon the nail body —A—. This mechanism consists of a rotary tool —c— having a cylindrical cutting or swaging face —c'— and a stationary tool —c²— having a concavely curved cutting or swaging face —c³— slightly separated from the face —c'— for permitting the entrance of the nail between said tools.

As best seen at Fig. 3 the face —c'— of the tool —c— is provided with diagonally extending ribs or cutting projections —c⁴—, and the face —c³— of the cutting tool —c²— is formed with opposite arranged diagonally extending ribs —c⁵— of less height or projection than the similar ribs —c⁴— of the face —c'—. As the nail passes between the tools —c—c'—, the ribs —c⁴— of the tool —c— form the spirally extending ribs —B— upon the nail body —A—, and the ribs —c⁵— of the tool —c²— form the transverse grooves —b— in said ribs —B—B—.

If desired, the surface —c³— of the cutter —c²— may be provided with cutting ribs crossing the ribs —c⁵— diagonally for lengthwise grooving the ribs —B—B— of the nail, or the cutting ribs for forming the ribs —B—B— upon the nail body may be formed by the stationary instead of the rotary cutter. Moreover the nail may be passed between opposing rotary cutters having their contiguous faces moving at unequal speed instead of between a stationary and a rotary cutter.

The described cutting or swaging apparatus is a particularly simple and practical means for forming the engaging surface upon the body —A— of my improved nail, but it is evident that said surface may be otherwise produced, and that my invention is not limited to any particular construction of mechanism for manufacturing the same.

The operation of my invention will be readily perceived from the foregoing description and upon reference to the drawings; it will be particularly noted that the body of the nail is not cut away, but that its surface is merely swaged or upturned for forming spirally extending ribs —B—; that these ribs are transversely grooved, and that the nail is economically manufactured, is easily entered, and is withdrawn only with considerable difficulty.

Having thus fully described my invention, what I claim as new, and desire to secure by Letters Patent, is—

1. As a new article of manufacture, the herein described nail, the same comprising a body, and a swaged spiral rib or projection upon the body provided with a series of transverse grooves, substantially as described. 55

2. As a new article of manufacture, the herein described nail, the same comprising a body, and a series of lengthwise parallel ribs or projections upon the body provided with a series of spiral grooves of less depth than the height of the ribs, substantially as specified. 60

3. As a new article of manufacture, the herein described nail, the same comprising a body, and a series of parallel swaged ribs extending spirally upon the body and provided with transverse spirally extending grooves, substantially as set forth. 70

4. As a new article of manufacture, the herein described nail, the same comprising a body, and lengthwise spirally extending ribs upon the body provided with transverse oppositely extending grooves, formed of less depth than the height of said ribs, substantially as and for the purpose described. 75

5. As a new article of manufacture, the herein described nail, the same being composed of a body having a plurality of swaged transversely grooved spiral ribs or projections on its surface, substantially as and for the purpose set forth. 80

6. As a new article of manufacture, the herein described nail, the same comprising a body provided with a tapering point, a head, and a plain upper end extending downwardly from the head, and transversely grooved spiral ribs extending upwardly from said tapering point, 90 to the lower extremity of the upper plain end of the nail, substantially as and for the purpose described.

In testimony whereof I have hereunto signed my name, in the presence of two attesting witnesses, at Syracuse, in the county of Onondaga, in the State of New York, this 9th day of March, 1893.

WILLARD C. LIPE.
